CENTRIFUGAL SEPARATOR

George J. Strezynski, Poughkeepsie, N. Y., assignor to The De Laval Separator Company, New York, N. Y., a corporation of New Jersey

Application September 24, 1938, Serial No. 231,459

15 Claims. (Cl. 233—17)

Centrifugal extractors, whether of small diameter and high speed or of large diameter and slow speed, must compete with gravity settling tanks.

Gravity settling tanks have no size limitations, whereas any increase in size of centrifugal extractors involves so great an increase in stresses that the speed must be reduced resulting in reduced efficiency.

In practically all commercial centrifugal extractors it is found that the stresses in the wall of the rotating cylinder are caused more by the weight of the walls than by the load due to the contained liquor. The self stress due to the weight of the wall is generally about 60% of the total stress.

It has been generally accepted that the strongest type of construction for a centrifugal bowl is substantially a cylinder rotating around its own axis; the main body of the cylinder being of monolithic structure, that is, made in one piece.

Long study and investigation caused me to seriously question the correctness of this principle. My work involved a comparison of cylinders rotating around their longitudinal axes with cylinders of the same dimensions rotating around an axis at right angles to their longitudinal axes. Analyses of the forces and dimensions of cylinders of the latter type indicated a large variation in performance depending on the relation between the longitudinal and transverse axes of the cylinder.

In the forepart of this description it will be convenient to refer to certain of the accompanying drawings, and therefore all of them will be first briefly described.

Fig. 1 is a diagram of a cylinder rotatable about its longitudinal axis. Figs. 2 and 3 are diagrams, in vertical and plan cross-section respectively, of a cylinder of the same dimensions as in Fig. 1 but rotatable on its short (transverse) axis. Fig. 4 is an end view of Figs. 2 and 3. Fig. 5 is a view, similar to Fig. 2 or 3, but of a cylinder of shorter length and greater width. Figs. 6 and 7 are diagrams illustrating the principle of my invention. Fig. 8 is a transverse sectional view of a centrifugal bowl taken through the center thereof perpendicular to its axis of rotation. Fig. 9 is a side view of the bowl of Fig. 8. Fig. 10 is a sectional view of the bowl of Fig. 8 taken on the line 10—10 of Fig. 8.

Figs. 1, 2 and 3 are diagrams of two cylinders of equal dimensions, the cylinder 1 in Fig. 1 rotating about its longitudinal axis and the cylinder 2 of Figs. 2 and 3 (Fig. 2 being a side view and Fig. 3 a plan) rotating about its transverse axis. In Fig. 1, the thickness of the cylinder wall must be

uniform. In Figs. 2 and 3 there is no such requirement because the load in the direction X decreases, and it is therefore advisable to reduce the thickness of the wall from the center toward the periphery.

The total stress in Fig. 1 at 15,000 R. P. M. is:

$$S = (\text{dia.})^2 \times (\text{rev.})^2 \left(1.03 + \frac{9.7 \cdot \text{dia.}}{2t} \right)$$

$$S = 37,500 \text{ lbs.}$$

In Figs. 2 and 3, the following table gives stresses in direction X at 7000 R. P. M.

Table A

	Weight	Radius	Force	Stress
Cylinder	Pounds	Inches	Pounds	Pounds
Ends	43.1	6.6	116,000	25,000
Liquor	2.75	15.0	28,600	4,100
	9.30	10.0	64,500	9,200
Total				38,200

The bursting stress in Figs. 2 and 3 is quite negligible. It may be seen on the plan view (Fig. 3) that as we proceed toward the end from A to D the bursting force becomes more and more parallel with the axis and therefore the bursting component becomes smaller and smaller. It is largest at point A, but at point A there is no liquid at all to superimpose its stress on metal stress. The liquid line is indicated by the dot and dash line. Also, as may be seen from the end view, Fig. 4, only a very small part of the metal is at full radius from axis Y—Y. In fact these bursting stresses are so low at this reduced speed of 7000 R. P. M. and at this small radius that the investigation disclosed the advisability of extending this analysis to a somewhat shorter cylinder but of greater diameter, as diagrammed in Fig. 5.

Table B gives the forces for a cylinder 3 dimensioned as in Fig. 5 at 6000 R. P. M.

Table B

	Weight	Radius	Force	Stress
Cylinder	Pounds	Inches	Pounds	Pounds
Ends	50.5	5.3	136,000	13,000
Liquor	6.25	12.0	39,300	3,600
	21.0	8.0	86,000	8,200
Total				24,800

Referring to Fig. 5, it may be seen that the tensile stresses along the axis X are considerably lower at a speed of 6000 R. P. M. but the bursting

loads are becoming noticeable and further analysis indicates that the bursting loads add sufficient to the stresses to bring them up to about 35,000 lbs., or nearly the same as in the two previous cases.

Now bearing in mind that the centrifugal effect varies directly as the radius at which the body of the liquor is spun, it also varies as the square of the speed of rotation and directly as the amount of liquor held in the vessel. Tabulating the values for the three cases involved gives the following results.

Table C

15	(R.P.M.): 1,000,000	Av. rad. in inches for center of liq. body	Total wt. of liquor	Product of three columns
20	Fig. 1.....	225	1.5	Pounds 9.3
	Figs. 2 and 3.....	49	10.0	9.3
	Fig. 5.....	36	8.0	4556 6050

It may be readily seen that there is a most favorable diameter and length at which a cylinder can be rotated at the right angle to its axis and give the maximum clarifying effect and at the same time provide very much larger volume for storage of any material to be removed from the liquor being clarified.

30 Actual tests made over a period of one year substantiated the above figures and allowed me to use a speed of rotation about twice as high as used in a cylinder of the same maximum peripheral diameter. That is a cylinder of 12 inch diameter and 48 inches from end to end was spun at 2400 R. P. M., whereas a centrifugal basket of 48 inches and 6 inches deep and 20 inches wide at the periphery is usually spun at 800 R. P. M. and in extreme cases at 1200 R. P. M.

40 The investigation of stresses in the end plates reveals that they are quite low if these ends are made semi-spherical or conical. For reasons explained later, the conical ends were found to be best.

45 Further work along these lines revealed that if two or more such cylinders are superimposed on each other so as to form a cross or star formation, the stresses in the individual cylinders are not exceeded, but on the contrary the bursting stress near the center is reduced. That is, it can be readily seen in Fig. 6 that the tendency of force f to bulge outward the wall w' of one of the cylinders 4 is counteracted by the reinforcing action of wall w^2 and wall w^4 . In the case of three cylinders 5 , as diagrammed in Fig. 7, this reinforcing effect is of such magnitude that a speed of 7000 R. P. M. is quite practical.

50 In practice the optimum conditions were found to be three such cylinders built into a monolithic star with some modification of the central portion to facilitate the casting or forging of the complete unit. Now if the values in Figs. 1 and 7 are tabulated the following results are obtained:

Table D

65	(R. P. M.): 10 ⁶	Av. rad. in inches for center of liq. body	Total wt. of liquor	Product of three columns
70	Fig. 1.....	225	1.5	Pounds 9.3
	Fig. 7.....	49	8.0	63.0 24,700

From Table D the clarifying effect is almost eightfold and the storage volume sevenfold as

great as in the cylinder rotating around its own axis.

Though analysis of the bursting stresses reveals that for best effect the length of the cylinder should be about 3 to 4 times its diameter and while the ends should be cylindrical or conical, the central portion is subjected to different types of forces and may be of square or rectangular construction. In fact, rectangular construction is preferable when two or more such cylinders are superimposed. The rectangular sides of three such oblong vessels form a hexagonal center portion which is well adapted for commercial construction and allows an ample central chamber for feeding the liquor and accommodating auxiliary means for such operation. This is shown in Fig. 7. The optimum condition is gained when the ends are cylindrical, oval or conical for about 25% of the length of the longitudinal vessel from each end and the central 20 50% is rectangular or square. The central portion does not perform any clarifying function but it functions only as a distributor of the liquor. A distributor whose hollow diameter equals or exceeds the transverse dimension of the clarifying vessel is one of the novel features of my invention.

Actual commercial tests revealed further advantages. Figs. 8, 9 and 10 illustrate a commercial bowl embodying the principle of Fig. 7. Its extreme diameter across the tips of the cones is 48 inches and the diameter or the short dimension of each vessel varies from 12 inches near the end to about 16 inches at the center. The central portion of each vessel is rectangular and merges into a cylinder which in turn ends in individual cones.

Each cone is fitted with a removable tip containing a small orifice. The orifice can be opened or closed at will by a needle valve operable by 40 mechanism in the central chamber and connected, through small openings in the central hexagonal chamber, to the said needle valve.

If a horizontal section is taken at any depth through one of the vessels comprising the unit in Fig. 8, the section will be oblong with walls fully streamlined without any violent breaks in the continuity of the stress flow.

The superiority of the construction just described is best demonstrable by a study of actual test figures obtained over a period of several months while testing the bowl against a standard commercial machine.

The standard machine in question was a 48 inch diameter extractor spinning at the usual speed of 800 R. P. M. A machine embodying my invention consisted of two 12 inch diameter cylinders at right angles to each other and 48 inches from tip to tip of each cylinder. The figures are given in Table E.

Table E

	Flow through machine in gals./hr.	Percent removal of solids	Concen- tration of solids (percent)
Standard mach.....	2,700	0.4	8.0
New mach.....	4,500	1.5	21.0

While it is believed that the essential structural features of the invention will be clear from the foregoing description, it may be advisable to more particularly describe the construction shown in Figs. 8, 9 and 10 illustrating in detail a preferred embodiment of my invention.

The bowl is preferably made in two parts—an upper half and lower half—which are welded together along the line x to form an integral unit which then comprises a central hub 10 and radiating therefrom six peripheral separating chambers 11, 12, 13, 14, 15 and 16 (see Figs. 8 and 10), spaced uniformly, that is, 60° apart, around the periphery of the hub. Each pair of diametrically opposite chambers (e. g., 11 and 12) together with the webs or tension members 20 aligning with their side walls and connecting them with the hub 10 constitute, in principle, a single cylinder such as is diagrammed in Fig. 5. The three cylinders comprising the entire bowl may be said to overlap at their central portions to form a central chamber 23, common to all cylinders, and small chambers 21 triangular in horizontal section and positioned outside the central chamber and between adjacent separating chambers. That is, one side of one of these cylinders comprises the side of one peripheral separating chamber, a tension member in the form of a web 20, a short arcuate section of the hub wall, another web 20 and the side of a diametrically opposite separating chamber, all these elements being located in substantial alignment and integral one with another and thus imparting to the whole structure maximum strength. The sides of adjacent cylinders intersect at the points 18 and the inner end of a web 20 constituting an inward prolongation of one of the side walls of one peripheral chamber is integral, not only with the hub 10, but also with the inner end of a web 20 constituting an inward prolongation of one of the side walls of another peripheral chamber spaced 120° from the first mentioned chamber. The webs 20 are not solid but are arranged to form an opening 19 through which the lighter (liquid) constituent separated in the adjacent peripheral separating chamber flows into the chamber 21 and from which it escapes through a discharge passage 22.

The mixture to be separated is admitted to the central hollow hub 23 through a stationary axial channel 24 and one or more stationary radial distributing nozzles 25.

It will be observed, by reference more particularly to Fig. 9, that the central parts of the cylinders, including the inner ends of the peripheral separating chambers, are rectangular in cross-section and that the rectangular walls at the inner end of each separating chamber merge into a cylinder and thence into a cone which terminates in (substantially) a point. Thus each separating chamber, except at its inner end, is approximately circular in cross-section. By "approximately circular" I mean to include a true circle, as when the inner part of the chamber is square (as in the drawing) and also an oval, which would be the shape if the inner part of the chamber were oblong. Variations in this respect are contemplated. Indeed, the peripheral chambers, especially the middle and outer end portions thereof, may have various shapes; the conical shape shown, however, having distinct advantages in the centrifugal separation of solids from liquids.

When the bowl is to be used for extracting solids from liquids, it is preferred to provide the following means for admitting the mixture to the peripheral chambers. Where two webs 20 join the hub 10 the wall (thickened at these points) is provided with openings in which are fixedly inserted discs 26 having therein drilled holes 27 near their peripheries. The mixture to

be extracted flows from the central chamber through these holes into the peripheral separating chambers. The holes are sufficiently small to prevent the entrance to the separating chambers of any large particles. Tubes 40 are also fixed in the same openings and convey the mixture to the chamber preferably radially beyond a point midway between said opening and the extremity of the cone.

In the separating chambers the solids are separated from the lighter liquid constituent and are discharged through orifices 28 in the point of the cone. Preferably each cone is fitted with a two-inch removable tip 29 containing an orifice 28 about $\frac{1}{8}$ of an inch in diameter.

The orifice 28 may be opened and closed by means of a radially movable needle valve 30, which extends slidably through a central orifice in the disc 26, its inner end extending loosely through the short end of a bell-crank lever 31, lock nuts being threaded on the inner end of the valve rod. The long arm of the bell-crank engages a circumferential groove in a spool 32 suspended from a rod 33 extending along the axis of rotation of the bowl upward (within the bowl spindle if the bowl is driven from above) to a point outside the bowl convenient for manual operation. It will also be understood that the rod 33 may be operated automatically to open and close the valve 30 at timed intervals. Mechanism for so doing is known in the art and is therefore not described.

Preferably the bowl is suspended from a spindle (34). The means for suspending and driving the spindle are not shown, as they form no part of the invention.

While the bowl is more particularly intended for use in the extraction of solids from liquids it is not limited to any particular use nor to the means shown for admitting the mixture to the bowl, nor to the discharge of the heavier constituent through peripheral outlets. It is obvious that if the bowl is adapted for the separation of two liquids it may be desirable to outflow both of them through a bowl neck, as is customary in such bowls. The adaptation of the bowl to different types of centrifugal separation is within the skill of centrifugal separator designers.

In the construction shown, the mixture to be separated is fed through a stationary channel 39 into the axial channel 24 and distributing nozzles 25 hereinbefore mentioned. The purified liquid discharges from the outlets 22 through the top of the bowl into a stationary channel 36. The solids are discharged into a stationary receptacle 37, whence they are conveyed away through a channel 38.

In conclusion, it may be stated that the radical improvement in performance hereinbefore explained in detail, as applicable to the embodiment of my invention shown in the drawings, is due mainly to four factors:

(1) Higher speed at the point of maximum diameter is possible than in any other commercial machine of corresponding size.

(2) Complete absence of slippage prevents re-mixing and breaking up of flocculated masses. In all commercial machines the main body of the liquor is contained in the central cylinder and as the liquid at each point of the diameter is rotating at a different lineal speed while it travels inward and outward, there is tremendous slippage between the different layers of liquid. This results in continuous breaking up of the chemical flocs to be precipitated. In a bowl embody-

ing my invention substantially all the liquid is contained in limited radiating vessels and no slippage is possible. The liquor is brought into each vessel by a tube of ample cross-section and extends to comparatively near the tip of the vessel so that the incoming liquid does not disturb the separated liquid. The introduction of the liquid and solids directly in line with the tip of the vessel allows the precipitation of the solids 10 at a point from which their removal is easiest.

(3) The heavy phase, solid or liquid, is concentrated in a very small portion of the vessel but at the maximum force available, and its prompt removal by suitable means, like an automatic or timed valve, leaves most of the vessel 15 available for clarification of the light phase.

(4) The high speed attained at the tips of these vessels, combined with the great depth of the liquid column above the tips of the vessels, 20 provides hydrostatic forces never reached before in a commercial machine. The pressure is 1300#/sq. in. in the bowl illustrated in Fig. 8, whereas in heretofore known commercial machines the pressure does not exceed 800#/sq. in. 25 This high hydrostatic pressure allows exuding of semi-solids much drier or more viscous than hitherto.

In considering these advantages and improvements the size of the machine must be kept in 30 mind. Several factors are involved, namely, speed, volume, diameter and depth. If we compare two bowls, one of which has twice the dimensions of the other one, the larger diameter bowl will have at the same rotation twice the linear speed at the periphery, but it will have four times as high self-stresses, eight times as much volume. When force, time and settling distance are taken into consideration, such bowl should have eight times the clarifying effect, but due to 40 the fact that the annulus of the larger cylinder has an area only four times as large as in the smaller bowl the velocity toward the center which determines the slippage is not the same but is twice as great and therefore the effect of slippage is not the same. For that reason there is 45 no analogy between commercial machines and laboratory apparatus. The conditions of stresses, design and clarification are radically different. It will be understood that my invention is intended more particularly for embodiment in 50 commercial machines. In using that term in the foregoing description I mean to be understood as referring to machines whose clarifying effect is determined by no smaller product of 55 volume and revolutions than 100,000 cc.-sec.

This application is a continuation in part of an application filed November 18, 1937, Serial No. 175,177.

What I claim and desire to protect by Letters 60 Patent is:

1. A centrifugal separator bowl comprising a central hub and peripheral separating chambers spaced sixty degrees apart, webs rigid with and constituting inward extensions of the side walls 65 of the chambers, each web of a chamber being connected and rigid with the hub and with a web extending from the side wall of a chamber spaced 120° therefrom, the two webs extending from the adjacent side walls of each two adjacent 70 separating chambers forming between them and the hub a lighter separated liquid outflow space communicating with the inner portions of both said adjacent chambers.

2. A centrifugal separator bowl comprising a 75 plurality of cylinders, each cylinder extending

equal distances on opposite sides of the bowl's axis, the longitudinal axis of each cylinder being perpendicular to and intersecting the bowl's axis, each cylinder intersecting the other cylinder or cylinders and thereby forming two opposite peripheral separating chambers rigidly connected together and a central space surrounding the bowl's axis common to the cylinders, the cylinders being substantially rectangular at their intersecting central portions and at the inner ends 10 of the separating chambers, the outer portion of each separating chamber being circular in cross-section.

3. A continuous centrifugal separator bowl comprising a central hollow chamber and a plurality of pairs of peripheral chambers, the chambers of each pair being arranged diametrically opposite each other, each side wall of a peripheral chamber being in substantial alignment with one of the side walls of the other chamber of the pair and tension members, constituting inward extensions of said two side walls, the inner ends of which are connected together, said tension members, as well as said two side walls, being all in substantial alignment and rigid each with 20 the others.

4. A centrifugal separator bowl comprising a plurality of pairs of peripheral separating chambers, the inner portion of each peripheral chamber being rectangular in cross-section and its outer portion being circular in cross-section, the side walls of the inner portion of each chamber extending on opposite sides of and substantially parallel to the bowl's axis and the top and bottom walls of such inner portion extending at 30 substantially right angles to the bowl's axis, the said side walls of the chambers of each pair being arranged diametrically opposite each other and rigidly connected together.

5. A centrifugal separator bowl comprising a central hollow chamber and three pairs of peripheral chambers, the chambers of each pair being arranged diametrically opposite each other, all the chambers being equally spaced apart around the central chamber, each side 40 wall of a peripheral chamber being in substantial alignment with one of the side walls of the other chamber of the pair and tension members rigid with the side walls of said chambers and constituting inward extensions thereof, the inner ends of opposite tension members being rigid with and connected together by an arcuate section of the central chamber.

6. A centrifugal separator bowl as defined in claim 5 in which the inner end of each tension 55 member merges and is rigid with the inner end of a tension member that constitutes a side wall extension of a peripheral chamber spaced 120° therefrom.

7. A centrifugal separator bowl as defined in claim 5 in which the inner end portion of each peripheral chamber is substantially rectangular in cross-section, so that opposite peripheral chambers are rigidly connected together throughout their height.

8. A centrifugal separator bowl as defined in claim 4 in which the outer portion of each peripheral chamber is of conical form.

9. A centrifugal separator bowl comprising a central chamber and six peripheral separating 70 chambers spaced sixty degrees apart, tension members rigid with the side walls of said chambers and constituting inward extensions thereof, the inner ends of opposite tension members being rigid with and connected together by an 75

5 arcuate section of the central chamber, the inner end of each tension member merging and rigid with the inner end of a tension member that constitutes a side wall extension of a peripheral chamber spaced 120° therefrom.

10. A centrifugal separator bowl comprising a central chamber and six peripheral separating chambers spaced sixty degrees apart, tension members rigid with the side walls of said chambers and constituting inward extensions thereof, the inner ends of each tension member being secured to the central chamber and merging and rigid with the inner end of a tension member that constitutes a side wall extension of a chamber spaced 120° therefrom.

15. A centrifugal separator bowl comprising a central hollow hub and a plurality of peripheral separating chambers radiating therefrom and rigid therewith, and outlet chambers for lighter separated liquid corresponding in number to the peripheral separating chambers, each outlet chamber being arranged outside said hub and between and communicating with two adjacent peripheral separating chambers and each peripheral separating chamber communicating with two adjacent outlet chambers.

20. A centrifugal separator bowl comprising a central hollow hub and a plurality of pairs of peripheral separating chambers, the chambers of each pair being arranged diametrically opposite each other, opposite side walls of the inner end of each peripheral chamber extending in one direction parallel to the axis of the bowl, said side walls intersecting the side walls of two adjacent peripheral chambers and extending substantially tangentially to and rigid with the wall of the hollow hub, arcuate diametrically opposite sections of which connect and align with the opposing side walls of the two separating chambers.

25. A centrifugal separator bowl comprising a central hollow chamber of substantially cylindrical shape and a plurality of pairs of peripheral chambers, the chambers of each pair being arranged diametrically opposite each other, each peripheral chamber being rectangular in cross-section at its inner end with two opposite sides at that end extending parallel to the axis of the bowl and two opposite sides extending at right angles to the axis of the bowl, the width of the inner end of each peripheral chamber, measured 30 between the side walls extending parallel to the

axis of the bowl, being substantially equal to the diameter of the central chamber, said side walls of each peripheral chamber being substantially tangential to the cylindrical wall of the central chamber, the adjacent side walls of adjacent chambers intersecting along a line parallel to the axis of the bowl and outside and spaced from the central chamber.

35. A centrifugal separator bowl comprising three rigidly connected cylinders, all the cylinders extending equal distances on opposite sides of the bowl's axis, the longitudinal axis of each cylinder being perpendicular to and intersecting the bowl's axis, opposite peripheral portions of each cylinder enclosing separating chambers, the three cylinders intersecting to form a central chamber and six relatively small chambers, arranged alternately with the six separating chambers, outside the central chamber, means to feed into the central chamber the mixture to be separated, there being openings between the central chamber and the separating chambers for passage from the former to the latter of the mixture to be separated and openings between each of said small chambers and the inner portions of two adjacent separating chambers for the passage from the latter to such small chambers of 40 separated lighter constituent.

45. A centrifugal separator bowl comprising three rigidly connected cylinders, all the cylinders extending equal distances on opposite sides of the bowl's axis, the longitudinal axis of each cylinder being perpendicular to and intersecting the bowl's axis; the three cylinders overlapping at their central portions and together forming a central hollow hub and, outside the hub six light constituent outlet chambers approximately triangular in cross-section, the non-overlapping outer ends of the cylinders forming six peripheral separating chambers, two walls of each of the triangular chambers being cut away to afford an opening for the escape from two adjacent separating chambers of separated light liquid, and means to feed the mixture to be separated to the central hollow hub, there being 50 openings between the central hollow hub and the six separating chambers for passage from the former to the latter of the mixture to be separated.

GEORGE J. STREZYNSKI. 55
